ELECTRONIC FLASH UNIT

Tadahide Okuno and Masahiro Karaki, Osaka, Japan,
assignors to Matsushita Electric Industrial Co.,
Kadoma, Osaka, Japan

Filed Dec. 24, 1974, Ser. No. 536,397

Claims priority, application Japan July 3, 1974

Term of patent 14 years

Int. Cl. D16—05

U.S. Cl. D16—42

FIG. 1

FIG. 2

FIG. 4

FIG. 3

FIG. 1 is a front perspective view of an electronic flash unit showing our new design;

FIG. 2 is a rear perspective view thereof;

FIG. 3 is a side perspective view of FIG. 1 showing the flash-head member rotated to an alternate position; and

FIG. 4 is a side perspective view of FIG. 1 showing the flash-head member rotated to another alternate position.

We claim:

The ornamental design for a electronic flash unit, as shown and described.
